UNITED STATES PATENT OFFICE

JOHN B. FELBER, OF CLEVELAND, OHIO.

DESIGN FOR A FRONT COVER PANEL FOR A VENDING MACHINE

Application filed October 11, 1930. Serial No. 37,239. Term of patent 7 years.

To all whom it may concern:

Be it known that I, JOHN B. FELBER, a citizen of the United States of America, residing at Cleveland, in the county of Cuyahoga and State of Ohio, have invented a new, original, and ornamental Design for a Front Cover Panel for a Vending Machine, of which the following is a specification, reference being had to the accompanying drawing, forming part thereof.

I claim:

The ornamental design for a front cover panel for a vending machine, as shown.

JOHN B. FELBER.
